Primary Examiner — Darlington Ly(74) *Attorney, Agent, or Firm* — Dunlap Bennett & Ludwig, PLLC(57) **CLAIM**

The ornamental design for a frame for electric motorbike or scooter, as shown and described.

DESCRIPTION

FIG. 1 is a front top right perspective view of the frame for electric motorbike or scooter, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front top right perspective view thereof, shown in use as part of a motorbike. The broken lines shown in FIG. 8 depict environment that forms no part of the claimed design.

1 Claim, 5 Drawing Sheets(56)
